UNITED STATES PATENT OFFICE.

JAMES NAYLOR, JR., OF ROCHESTER, NEW YORK.

BARREL-HOOP MACHINE.

SPECIFICATION forming part of Letters Patent No. 243,292, dated June 21, 1881.

Application filed April 20, 1881. (No model.)

To all whom it may concern:

Be it known that I, JAMES NAYLOR, Jr., a citizen of the United States, residing at Rochester, in the county of Monroe and State of New York, have invented certain new and useful Improvements in Barrel-Hoop Machines; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to a machine for the combined purpose of dressing and rendering wooden barrel-hoop blanks; and it consists in the combination and arrangement of parts in such a manner that tapered hoop-blanks of 20 any width are dressed or the corners rounded off by the operation of the machine.

The object of this improvement is, first, to construct a machine capable of dressing any width of hoop-blank; second, to allow the blanks to be fed straight through the machine; third, to hold the blank accurately to the action of the cutters; fourth, to prevent clogging of shavings and to relieve it from broken pieces, which often get wedged in; fifth, to render or 30 limber the dressed blanks, as will be hereinafter described.

In the drawings, Figure 1 is a side elevation; Fig. 2, a front elevation; Fig. 3, a plan of table, lower rollers, and their shafts; Fig. 35 4, a view of the dumping arrangement of table, and Fig. 5 a detailed view, showing section of dressed hoop-blank, cutter, and table.

A A represent the frame of the machine. Power is communicated from a counter-shaft 40 located overhead by the belts B B'. The cutter-head is driven by the belt B independently, the belt B' driving the feed-pulley c, secured to the shaft D, on which is the pinion E, engaging with both spur-gears F F, secured to the lower 45 roller-shafts, G G. The upper rollers, on account of their large diameter, do not necessarily require to be geared.

H H are smooth unyielding feed-rollers, being of larger diameter than heretofore, so as to 50 feed more effectually. H' H' are smooth unyielding feed and pressure rollers, and are made

larger than the others, H H, so as to strain the hoop-blanks in passing through the machine. All these rollers are run in positive or rigid bearings, the rear ones being arranged out of 55 square with a line of the passage of the hoop-blanks, as shown in Fig. 3, the dotted line x x being at right angles to the line of passage of the blanks. This, together with the shoulders h h h' h' h', constitutes the means by which 60 bended and narrow hoop-blanks are kept to an exact position when acted upon by the cutters P. By this arrangement hoop-blanks of all widths can be dressed, as there are no confined guides for the blanks to pass through. The 65 lower rollers are provided with angular recesses coinciding with the table, as shown in Fig. 3. The upper ones are straight, as shown in Fig. 2. A most important purpose which they perform is to render or limber the blanks, so that 70 breakage in coiling is prevented. Immense pressure is brought to bear by forcing, or rather feeding, a blank three-eighths of an inch in thickness through an opening only a quarter of an inch. By this effective arrangement the 75 wet hoop-blanks are nearly dried and the nature of the woody fiber entirely changed, possessing better qualities for its purpose. Barrel-hoops so made are stronger, and can be coiled without restreaming or boiling. Although the 80 blanks are compressed in the operation, the compression given by the rollers does not remain, but, on the contrary, it assumes its shape given by the action of the cutters. These 85 hoop-blanks, when operated upon, are always steaming hot and saturated; hence these various devices are to serve the condition of the same. In cutting the blanks there is more or less variation, and to provide for this the front rollers are set to meet the thinnest blank. 90 Consequently the thicker ones are more or less compressed, as the openings between the rollers are always the same. Thus the pressure exerted to feed the blanks is given by the blanks in contradistinction to weights or springs which 95 have heretofore been used.

I is the table, provided with two or more angular recesses, which coincide to the taper of the hoop-blank. Thus the shoulders h h h are formed, which serve as guides for the 100 blanks, and against which the rollers H' H', being out of square, are constantly forcing the

same. This table is so made as to be quickly dumped. I prefer to hinge it and support it on the outer edge, as shown in Fig. 4. This is for the purpose of relieving the machine of 5 broken pieces, which often get wedged in between the table and press-bars. In Fig. 1 the table is shown in place; in Fig. 4, dumped, so as to allow the pieces to fall out. As soon as 10 the support is taken away it falls by its own gravity. In machines without this device a stoppage of all parts is absolutely necessary, together with a loosening of parts; but now in 15 and by the use of this improvement it is done in an instant, without any stoppage whatever 15 of the working parts.

The casting or piece N, to which the table is hinged, has also the press-bars o o, solid or secured firmly to it, the whole being vertically adjustable to the cutter-head P, which has 20 secured to it cutters which conform in shape to the outside of a barrel-hoop, as shown full size in Fig. 5. These cutter-heads revolve rapidly in rigid bearings and dress or shape the blanks on the outside as fed through the machine.

25 A pivoted arm, M, is attached to the casting or support N in such a manner as to support the table I when said arm is in a vertical position, and affords a ready means of dumping the table by being turned upon its pivot 30 so as to withdraw its support, as shown in Fig. 4.

The vertical adjustment of parts holding the blanks while being dressed by the cutters is accomplished by means of the set-screw Q.

35 It must be observed that the table being dumped does not effect the press-bars, and when the press-bars are adjusted to the cutters the table is also adjusted by the same means, the blanks being always of the same 40 thickness.

The trouble with machines of this class is the constant clogging of the parts with shavings, slivers, and broken pieces, which if wet make it still worse. In the present 45 case devices are used and the various parts are so arranged that there is no chance for dross to accumulate, or should it happen to do so it passes out freely before it causes any annoyance.

50 In advance of the front feed-rollers are the openings for feeding in the blanks. These openings are made as large as possible, the limit being so that two blanks cannot enter together. Attached to the frame is the lower 55 piece, J, as shown in Fig. 1, and secured adjustably to it is the upper piece, K. Each of these pieces have angular recesses, one reverse of the other, so that when put together the oblong openings are the result, and by moving 60 the upper piece, K, in or out said openings are made of any required width. To feed the blanks rapidly and always have the same enter the openings, the shields L are so arranged of different sizes as to guide the blanks 65 exactly to the openings.

The operation of the machine is as follows:

Hoop-blanks are fed to the machine by being presented laterally to the shields L, which, being of different sizes, the smallest outside and tending inwardly direct to the openings, 70 enable the operator to feed easily as well as rapidly. The blanks are caught by the front feed-rollers, H H, which tend to throw them out in front and in beyond, as shown by the arrow in Fig. 3. This is caused by different 75 diameters bearing on the surface of the blank. As it passes along it comes in bearing contact with the shoulders h h h of the table, which, together with the table I and press-bars o o, hold the blank in exact position while being 80 acted upon by the cutters. It then is caught by the rear feed and pressure rollers H' H', which, being larger in diameter, pull or strain on it to keep it tight between the rollers. These rollers H' H' also squeeze the fibers together, 85 so that in coiling they lay more readily together, and hence do not break. The tendency of these rear rollers is exactly the same as the front ones. This being wrong, it is counteracted by placing the shaft out of square, as before described, and by this means the dressed blanks come square out of the machine.

I am aware that hoops have heretofore been formed by first feeding the blanks between a roller having a series of corrugated rings and 95 intermediate grooves and a cutter-head provided with a series of dividing-cutters and cutters having concave faces, whereby the hoop-blanks are divided and rounded at their corners, and then passed, in an inclined position, 100 upon an endless bed or apron having a series of inclined faces arranged beneath a roller having cones corresponding with said inclined planes to a horizontal cutter-head carrying a straight-edge cutter, which planes off the raised 105 or inner corners of the hoop; but this I do not claim.

Having thus described my invention, what I claim as new, and desire to secure by Letters Patent, is—

110 1. The smooth unyielding feed and pressure rollers, set rigidly, the lower ones coinciding to the angular recesses of the table, the upper ones being straight, in combination with the table, press-bars, and cutter-head, as and for 115 the purposes herein set forth.

110 2. The combination of rigid feed-rollers, shoulders h h h and h' h' h', table I, press-bars o o, and cutters coinciding to the outside shape of a barrel-hoop, all arranged and operating in the manner as herein shown and described.

120 3. The feed and pressure rollers H' H', set out of square with the line of passage of the hoop-blanks, and the front rollers, H H, set square with said line, in combination with the shoulders h h h of the table I and the shoulders h' h' h' in advance of the front rollers, substantially as and for the purpose specified.

125 4. The combination, with the cutter-head and feed-rollers, of a hinged table provided with a pivoted arm or lever, whereby the said 130 table is rendered capable of being instanta-

neously dumped and replaced in position independent of its vertical adjustment to the cutter-head, substantially as set forth.

5. The combination, with the cutter-head, of the press-bars *o o* and hinged table I, attached to a suitable support and adjustable with relation to the cutter-head by a common means, for the purpose of affording a ready adjustment of the hoop-blank to the action of the 10 cutters, substantially as described.

6. The smooth unyielding feed-rollers and cutter-head provided with cutters which con-

form in shape to the outside of a barrel-hoop, in combination with the shoulders *h h h* of the table I and the shoulders *h' h' h'* in advance of 15 the front rollers, as and for the purpose shown and described.

In testimony whereof I affix my signature in presence of two witnesses.
